SIGNAL RECORDING AND REPRODUCING

Ferdinand C. W. Thiede, Hempstead, N. Y., assignor to B. A. Proctor Company, Inc., New York, N. Y., a corporation of New York

Application August 22, 1940, Serial No. 353,612

20 Claims. (Cl. 179—100.11)

This invention relates to a signal recording and reproducing device, and more especially to a device of the type in which a record of the signal is inscribed in the form of a sound track on a movable record. Such a device is described in application Serial No. 218,082, filed July 8, 1938, in the name of Barton A. Proctor and Ferdinand C. W. Thiede. In said application an audio frequency amplifying device is disclosed and in association with which a switching device is provided, whereby a reproducing device may be connected with the input circuit of the amplifier and its output circuit connected with a loudspeaker in which the recorded signal is reproduced. In another position of the switching device, the output circuit of the amplifier may be connected with a recording unit, which records a sound track corresponding to the signal on a movable record, the switching device also causing the connection of a microphone to the input circuit of the amplifier, into which microphone the operator dictates the communication to be recorded. In the aforesaid application, the feed of the record is initiated by the lowering of a feed roller into engagement with the record surface by means of a manually controlled lever forming part of the recording device.

A recording and reproducing device of a similar type is disclosed in patent application Ser. No. 281,811, filed June 29, 1939, in the name of Barton A. Proctor, but in which the lowering of the feed roller into engagement with the record may be controlled from a remote point, at which a manually operated switch is provided. This switch is connected through a circuit which terminates in a solenoid disposed near the record, and the actuation of which operates a ratchet device which in turn rotates a cam, which permits the feed roller to be urged against the surface of the record under the bias of a spring. The rotation of the record then continues until the switch is again actuated to complete the circuit leading to the solenoid whereupon a further rotation of the ratchet device causes a high point on the cam to engage the lever carrying the feed roller and move the feed roller off the record, which immediately stops.

A main purpose of the present invention is the provision of means whereby the manual operation of a switch, such as that just described, to commence the feeding of the record is not required, but in which the starting and stopping of the signal recording device is controlled automatically in response to the tone modulations of the signal to be recorded. Where the signal to

be recorded consists of speech, the starting and stopping of the recording device is automatically controlled by the voice of the operator or dictator.

According to a further object of the invention, where the signal to be recorded consists of a radio transmission, the starting and stopping of the recording device is automatically controlled in response to the reception of the carrier wave by means of a radio receiver preferably disposed near the recording device.

In further pursuance of this object, the arrangement is preferably such that the rotation of the record on which the recording is to be made is initiated as soon as the carrier wave is received while the recording stylus itself is actuated by means of electrical currents corresponding to the signal modulation frequency which are detected and amplified in the receiver. These signal modulations may be of any preferred type and may consist for example of speech, music, code signals or any other known type of signal impulses.

A further object of the invention is the provision of means for supplying energizing currents to the recording device which provides for the continued feeding of the record during short intervals normally existing between successive portions of the signal, such as short pauses between words or sentences therein, but which automatically interrupts the feeding of the record at the end of the communication or signal or if the signal is purposely interrupted, resulting in a long interruption therein. The means which controls the feeding of the recording device preferably comprises a slow acting or delay relay, which serves to insure the contact of the drive roller with the rotating record during the short interruptions normally present between successive portions of the signal, but which permits the drive roller to be disengaged from the record in order to stop its rotation at the termination of the signal. According to one embodiment of the invention, this delay relay is energized by the same audio frequency amplifier which supplies the currents to operate the recording stylus.

As an alternative means for actuating such a delay relay, it is a further object of the invention to provide a sound pressure relay which is preferably disposed adjacent to the recording microphone and which closes the energizing circuit of the delay relay in response to the sound waves generated by the operator's voice. This sound pressure relay is preferably of the type which closes the relay circuit by means of a pair of cooperating contacts, one of which is actu-

ated by a diaphragm forming part of the relay and which is vibrated by the incident sound waves of the operator's voice.

Where the communication or signal to be recorded consists of several recordings spaced apart by substantial intervals on the same record, it is a further object of the invention to provide means whereby the signal may be continuously recorded, without any interruptions between its several parts, on a second record. In so doing, the second record is automatically started at the commencement of each separate portion of the recorded signal and automatically stopped at the end thereof, whereby a continuous record of the signal is secured without any interruptions therein on the second record. This arrangement also provides means whereby the recordings on a plurality of small records may be readily transferred as a continuous recording onto a single large record.

Other and further objects of the invention will become apparent to those skilled in the art as the description thereof proceeds. For a better understanding of the invention, reference is made to the accompanying drawings wherein similar parts are indicated by the same reference numerals and in which:

Fig. 1 is a diagrammatic representation of certain parts of a recording and reproducing device embodying the invention, including a circuit diagram of its electrical connections;

Fig. 2 is a diagrammatic representation of a device similar to that shown in Fig. 1 with certain modifications in the circuit connections thereof;

Fig. 3 is a diagrammatic representation of a device similar to that shown in Fig. 2 arranged for transferring previously recorded signals onto a record;

Fig. 4 is a plan view of a record adapted for use with the recording device shown in Fig. 3;

Fig. 5 is a diagrammatic representation of certain parts of a recording and reproducing device and its circuit connections embodying a modified form of the invention; and

Fig. 6 is a diagrammatic representation of a recording and reproducing device illustrating a further modification of the invention adapted for recording radio signals and including a circuit diagram showing portions of a connected radio receiver.

The present invention relates to a recording and reproducing device of the type disclosed and claimed in the above referred to application, Serial No. 281,811. Referring to Fig. 1, the device is shown as comprising a reproducing unit 1 having a stylus 2, a recording unit 3 having a stylus 4, shown in engagement with a thin flexible record 5. The lower surface of the record 5 is shown in engagement with a lower feed roller 6, secured to a shaft 7, carrying a large pulley 8, which is driven by means of a belt 9 from a motor pulley 10 of an electrical motor 11, supplied with current from the power lines L, upon the closure of a switch 12. For simplicity the record 5 has been illustrated as plane, but it will be understood that it is preferably curved over a turtleback support, as shown in the aforementioned applications.

Mounted above the record and opposite the feed roller 6 is an upper feed roller 13 which is rotated in the opposite direction to feed roller 6 by the pulley 8 through means not herein shown, when brought into engagement with the record. The roller 13 is mounted on an arm

14 pivoted at 15, and having a tail piece 16 biased upwardly by means of a spring 17. The mechanical means for moving the feed roller 13 into and out of engagement with the record 5 is similar to that disclosed in application No. 281,811 and comprises a shaft 18 carrying a ratchet wheel 19, and a pair of cams 20 and 21, each of which has three high points and three low points as shown. For rotating the ratchet wheel 18 a pawl lever 22 is pivoted on the shaft 18 and carries a pawl 23 adapted to actuate the ratchet. For rotating the pawl lever 22, a solenoid having a winding 24 is provided, the plunger 25 of which is connected by means of a link 26 to the pawl lever 22. Energization of the solenoid coil 24 causes the lowering of its plunger 25 resulting in a single step of rotation to the shaft 18 and the cams 20, 21 through the pawl 23 and its ratchet wheel 19. As soon as the flow of current through the coil 24 is interrupted, a spring 27 returns the link 26 to its upper limit of movement and thereby carries the pawl backward one tooth space relative to the ratchet wheel 19.

Important features and objects of the present invention have to do with the means for controlling the energizing current of the solenoid 24. The circuit connecting the coil 24 across the supply lines L is shown as comprising a lead 28 and a lead 29 terminating in a movable switch blade 30 disposed between the contacts 31, 32 which are connected to a similar pair of contacts 33, 34 by the upper and lower conductors 35, 36. The other side of the lines L is connected to the armature 37 of a delay or slow acting relay 38, the end of the armature 37 being disposed between the contacts 33, 34 as shown. The circuit of relay 38 includes a battery 39 and is adapted to be closed upon the energization of a quick acting or audio relay 40, having an armature 41.

In the embodiment of the invention shown in Fig. 1, the winding of relay 40 is energized by currents corresponding to the signal modulations to be recorded by means of the circuit shown, including the secondary winding 42 which is coupled to the first stage of an audio frequency amplifier of the type disclosed in the aforesaid application Ser. No. 218,082. This amplifier comprises the amplifying tubes 43, 44 and 45 which are connected together by the circuit shown and which are supplied with energizing current by means of a rectifier 46 and filter device 47. Also, as disclosed in said application, a manually operable switch control shaft 48 is provided, for the operations of recording or reproducing, this shaft being provided with the switches 49, 50, 51 and 52. A jack 53 is connected to the switch arms 51, 52 so that either a microphone-speaker 54 or a telephone search coil 55 may be plugged in and selectively connected to the primary winding 56 of the amplifier input transformer 57.

For recording a communication spoken before the microphone 54, its circuit is plugged into the jack 53 and the power switch 12 closed to start the motor 11, which causes the rotation of the lower feed roll 6. The recording unit 3 is then lowered into the position shown, with its stylus 4 in engagement with the record adjacent to its drive spindle by means of the manual control device (not shown) described in said application Ser. No. 281,811. The voice currents generated by the microphone 54 in primary winding 56 are amplified in the tubes 43, 44 and 45, the amplified currents appearing in

the secondary winding 58 of the output transformer 59 serving to vibrate the recording stylus 4 and cause it to form a corresponding sound track in the record 5. Simultaneously, the amplified voice currents appearing in the secondary winding 42 energize the quick acting relay 40 causing its armature 41 to close the circuit through battery 39 and delay relay 38 and cause its armature 37 to engage the upper switch contact 33. This completes the circuit connecting the coil of solenoid 24 with the power mains L, causing the downward movement of plunger 25 and the advancement of the ratchet wheel 19 one step by the pawl 23. The withdrawal of the high spot of cam 20 away from the tail arm 16 causes the feed roller 13 to be lowered into engagement with the upper surface of record 5 at a point directly opposite to its point of engagement with the lower feed roll 6. Due to the small mass and weight of the record, it commences to rotate at once and form the sound track in cooperation with the stylus 4. Advancement of the ratchet wheel 19 one step also causes a high spot on the cam 21 to move away from a spring 60 connected to the switch blade 30 through an insulating rod 61. Lowering of the switch blade 30 into contact with lower contact 32 breaks the energizing circuit of solenoid 24 at contact 31, thus permitting the spring 27 to elevate the plunger 25 and return the pawl 23 to its initial position, as shown. During normal brief interruptions in the communication, such as the short intervals between words and sentences therein, the armature 37 is maintained in its upper position in contact with contact 33 so that no further actuation of solenoid 24 occurs and a continuous drive of the record 5 is assured by the feed roller 13 remaining in contact with its surface. This action continues as long as the signal modulations cause the armature 41 of relay 40 to be actuated and cause the energization at brief intervals of the delay relay 38. At the termination of the dictation or other type of signal to be recorded, no energizing current passes through the winding of relay 40 to vibrate its armature 41 so that the circuit of the delay relay 38 is broken and its armature 37 drops down into contact with switch contact 34. Closure of this switch causes the energizing circuit of solenoid winding 24 to be completed, the switch blade 30 being at this time in engagement with contact 32, and the plunger 25 to be pulled down. This causes the advancement of the ratchet wheel 19 one step through the action of pawl 23, thereby causing a high spot on pawl 20 to depress the tail piece 16 and move the feed roller 13 into the position shown in Fig. 1 out of engagement with the record 5 so that rotation of the record ceases immediately, the record not being mounted on a rotatable turntable whose inertia would continue its rotation for an appreciable period of time. Simultaneously with the raising of feed roller 13 from the record, a high spot on cam 21 elevates the spring 60 causing the switch arm 30 to raise and break the energizing circuit of solenoid 24 at lower contact 32 and to remain in its upper position in engagement with contact 31, as shown. The plunger 25 is automatically returned into its upper position under the action of the spring 27 so that all parts of the feed control device are again in their initial positions, as shown. It is thus seen that the modulations of the signal to be recorded automatically cause the immediate

rotation and feed of the record 5 and the actuation of the recording stylus 4.

Where the signal or communication to be recorded consists of a telephone conversation, the microphone 54 is replaced by the telephone search coil 55 which is placed in inductive relation with the telephone line or an inductance coil in such line. The method of recording and operation of the device is the same as that just described, so that a detail description thereof is not required, the feed of the record being initiated by the amplified telephone line currents actuating the audio relay 40. Upon completion of the telephone conversation, the relay 40 is no longer energized and the lowering of its armature 41 causes the stoppage of the record 5 in the manner above described.

To reproduce the recorded signal, the recording unit 3 is raised and the reproducing unit 1 lowered into position with its stylus 2 in engagement with the inner end of record groove by a manual control device (not shown) of the type described in the aforementioned application Serial No. 281,811. The switch shaft 48 is simultaneously thrown to the right and the circuit of the microphone speaker 54 plugged into jack 53. Electrical currents corresponding to the recorded signals are developed in the reproducer unit 1 and applied to the grid of amplifier tube 44 through the circuit shown including switch arm 49. These currents are amplified in the tubes 44 and 45 and applied to the speaker 54 where they are translated into corresponding sound vibrations.

The recording and reproducing device shown in Figure 2 is similar in construction and operation to that shown in Figure 1, with the exception that resistance coupling is used between the amplifying stages 43 and 44, the condenser 63 replacing the secondary winding 62 of Figure 1 and the modulating currents for energizing the quick acting relay 40 are supplied through the circuit shown including the condenser 64. It will be obvious from the foregoing description, that upon the operation of relay 40 due to its energization by currents of the signal frequency impressed thereon by condenser 64, that the record 5 will be instantly rotated due to the lowering of feed roller 13 into engagement with its surface and that such feed will continue as long as operation of the relay 40 continues. Upon the termination of the communication, the plate current of tube 43 will assume a steady value so that relay 40 is deenergized and causes the automatic stopping of the record in the manner above described in connection with Figure 1.

The embodiment of the invention shown in Fig. 3 is generally similar to that shown in Fig. 1, the corresponding parts being indicated by the same reference characters. Another motor, however, is connected with the supply lines L for driving a second record 5a by means of drive connections similar to those already described in connection with Figure 1, corresponding parts of the driving mechanism being indicated by similar reference numerals with the subscript *a* added. For lowering the feed roller 13a into engagement with the surface of record 5a, a manual control arrangement of the type described in application Ser. No. 218,082 is illustrated schematically as comprising a rotatable shaft 65 adapted to drive a cam 66 through the gear wheels 67, rotation of shaft 65 into the position shown in Figure 3 causing the stylus 2a of the reproducer

1a to be lowered into engagement with the record and movement of cam 66 away from tail piece 16a of the feed roller arm 14a permitting the feed roller 13a to be moved into driving engagement with the surface of the record under the bias of spring 17a. The resistance coupling arrangement between the plate circuit of tube 43 and grid circuit of tube 44 includes condenser 63 and switch arm 49, similar to that shown in Figure 2, and also includes a jack 68 which may be plugged into the circuit. The record 5a may be of the type shown in Figure 4, on which a communication interrupted at intervals has been recorded, or on which a plurality of different communications have been recorded at spaced intervals. Those portions of the record representing communication are indicated by the reference characters C, C' and C'', the spiral record groove between the inscribed record portions being designated by the reference characters S and S'. Instead of the coil 42 which supplies the energizing currents to the winding of relay 40 being connected to the output circuit of tube 43, as shown in Fig. 1, a corresponding coil is shown at 42a as being coupled to the output circuit of amplifier 44.

For recording the several spaced apart or interrupted communications on the record 5a as a single continuous recording on the record 5, the jack 68 is plugged in and the shaft 65 adjusted into the position shown, to lower the reproducing stylus 2a into contact with the surface of the record 5a at the inner end of the spiral groove thereon. As the feed of the record proceeds, upon the vibration of the stylus 2a at the commencement of the inscribed portion C, the amplified signal currents appearing in the coil 42a cause the operation of audio relay 40, the operation of relay 38, and the lowering of the feed roller 13 into engagement with the record 5 with the consequent recording of the communication C in the manner above described in connection with the operation of Figure 1. The recording continues until the end of record portion C passes under the stylus 2a, whereupon no energizing voltage is developed in the coil 42a to operate the relay 40, whose release results after a short interval in the release of the delay relay 38 and the elevation of feed roller 13 from the record 5, which immediately stops, as above described in connection with Fig. 1. This record remains at rest while the reproducing stylus 2a is passing over the spiral groove in the portion S between the record portions C and C'. As soon as the beginning of the recording C' passes under recording stylus 2a, the amplified signal currents developed in coil 42a again energize relay 40, delay relay 38 and cause the feed roller 13 to be again lowered into engagement with the record 5 and the recording stylus 4 to record thereon the communication represented by C' on the record 5a. This process continues until all the communications represented on the record 5a have been transferred as a continuous record onto the record 5.

Instead of the communication portions C, C' and C'' being disposed on a single record, they may be disposed on separate small records which may be placed on the record spindle one after another in the position shown by the record 5a. In this case, as soon as the reproducing stylus 2a is actuated at the inner end of the recording on the first record, the feed roller 13 is automatically lowered into engagement with the surface of the large record 5 which immediately commences to rotate. This rotation continues and the record-

ing stylus 4 records the communication previously recorded on the first small record. Upon the reproducing stylus 2a reaching the end of the recording on the first record 5a, the feed roller 13 is automatically raised from the record 5 in the manner heretofore described, and rotation of the record 5 immediately ceases. The next small record is then inserted in the reproducing machine and the process repeated until the contents of all the small records has been recorded on the single large record 5 as a continuous communication.

The embodiment of the invention shown in Fig. 5 is similar to that shown in Fig. 2 except that instead of deriving the actuating currents for the delay relay 38 from the amplifier circuit through the circuit connection including condenser 64 (Fig. 2), they are derived from a sound pressure relay 69 having a diaphragm 70 which carries a movable contact 71 adapted to engage a fixed contact 72 connected with the local battery 39. The sound pressure relay 69 is preferably disposed adjacent to the microphone 54 so that as soon as the operator commences to dictate before the microphone, the sound pressure generated by his voice causes the diaphragm 70 to vibrate and close the circuit of the delay relay 38. The closure of this circuit causes the automatic lowering of the feed roller 13 and the rotation of the record 5 in the manner above described. As the dictation continues, the relay 38 is energized at frequent intervals by the closure of contacts 71-72 so that the relay armature 37 is sustained and rotation of the record 5 continued, the communication being continuously recorded thereon by the recording stylus 4. At the termination of the dictation, the diaphragm 70 remains at rest with the contacts 71-72 separated, causing the release of relay armature 37 after a short interval and the elevation of feed roller 13 and consequent stoppage of the record 5 in the manner above described in connection with Fig. 1. In this embodiment also, it will be understood that if for any reason the dictator makes a long pause as, for example, several seconds, in the dictation, the delay relay 38 operates to release its armature 37 and the record 5 is automatically stopped. Upon resuming the dictation, the relay 38 is again energized, the feed roller 13 again lowered into engagement with the record 5 and its rotation continued as before.

The embodiment of the invention shown in Fig. 6 is generally similar to that shown in Fig. 2 but instead of the energizing currents being supplied to the winding 56 of the transformer 57 by the microphone 54, they are supplied by the detector stage 73 of a radio receiver R herein illustrated as of the superheterodyne type and comprising a first detector 74, a local oscillator 75, and one or more intermediate frequency amplifier stages 76. The receiver also preferably comprises an automatic volume control device 77 which is coupled to the output of the amplifier stage 76 and controls its grid bias and hence its transconductance, inversely as the strength of the carrier to which the receiver is tuned. Any suitable known type of automatic volume control device may be utilized and while a superheterodyne type of receiver has been described, it will be understood that a radio receiver of the tuned radio frequency type having a plurality of tuned radio frequency amplifying stages may be substituted therefor. The circuit connecting the output of the receiver R to the amplifier stage 43 comprises the primary coil 56 and a switch arm 78 secured

to the switch shaft 48a. Signalling current is supplied to the first detector 74 from any suitable type of antenna device 79.

In this embodiment of the invention the starting and stopping of the record 5 is controlled by a sensitive relay 80 whose winding is connected in series between the output circuit of amplifier 76 and a source of positive plate potential B. The armature 37a of relay 80 operates between a pair of contacts 33a and 34a corresponding to the contacts 33 and 34 of Figs. 1 and 2.

In using the device to record a broadcast program comprising speech, music or other type of signal, the jack 53 is plugged in to connect the microphone-speaker 54 to the output of the amplifier stage 45 and the switch shaft 48a adjusted into the position shown. With the power switch 12 closed and the recording unit 3 lowered into the position shown with its stylus 4 in engagement with the record 5 near its center, and with the receiver untuned to the desired carrier frequency, the plate current of amplifier tube 76 passing through the winding of relay 80 is sufficient to cause its armature 37a to be retained in contact with the contact 34a, as shown. Upon tuning the input circuit 81 of the receiver to the desired carrier frequency by any suitable type of tuning means as, for example, the variable condenser 82, the action of the automatic volume control device 77 causes the negative bias voltage on the grid of tube 76 to increase and thus decrease the plate current of the tube. This reduced current passing through the winding of relay 80 causes its armature 37a to move into engagement with contact 33a. In the manner above explained in connection with Fig. 1, this causes the feed roller 13 to be moved into engagement with the surface of the record 5 and the record to rotate under the recording stylus 4. The incoming signal modulations are detected in the detector 73 and after being amplified in the amplifier stages 43, 44 and 45 are applied to the recording unit 3 through the circuit shown, including the secondary winding 58 and switch arm 50, the signal modulations thus being recorded on the record 5 by the recording stylus 4. This recording continues as long as the carrier frequency is received or until the input circuit 81 is detuned. In either of these events, the action of the automatic volume control device 77 causes the grid bias of tube 76 to decrease and its plate current to increase. The increased current through the winding of relay 80 causes its armature 37a to be pulled into engagement with contact 34a, as shown, and the feed roller 13 to be elevated above the record 5, causing the latter to immediately come to rest, in the manner above described in connection with Fig. 1. During the recording process, the signals being recorded are reproduced in the speaker 54 so that the operator is at all times aware whether a modulated signal is being received. From the above description, it is apparent that the starting and stopping of the recording mechanism is automatically controlled by the radio signal to be recorded.

I have described what I believe to be the best embodiments of my invention. I do not wish, however, to be confined to the embodiments shown, but what I desire to cover by Letters Patent is set forth in the appended claims.

I claim:

1. A device for recording a signal having tone modulations on a thin flexible disc record of

small mass and inertia comprising, in combination, a stationary member arranged to engage the lower face of and support the record, recording means adapted to record the signal on the record, means comprising at least one feed wheel for rotating the record with reference to the recording means, means responsive to the tone modulations of the signal for automatically moving said feed wheel into direct engagement with the surface of the record to rotate the record and means comprising an electron discharge tube amplifying device for energizing the signal recording means by the amplified signal modulations.

2. In a device for recording a signal having tone modulations on a thin flexible disc record of small mass and inertia comprising, in combination, a recording unit having a stylus arranged to engage the surface of the record, a curved stationary member arranged to engage the lower face of the record for supporting it, means for rotating the record comprising a friction roller adapted to engage the face of the record itself, control means for normally maintaining said friction roller out of engagement with the face of the record, means responsive to the tone modulations of the signal for moving said friction roller into engagement with the face of the record to rotate the record under the stylus, means responsive to a cessation of the signal modulations for automatically rendering said control means effective to move the friction roller away from the face of the record, and means for energizing the recording means by the signal modulations.

3. A device for recording a signal having tone modulations on a thin disc record of small mass and inertia comprising, in combination, stationary means arranged to engage the lower face of the record to support it, means comprising a pair of opposed feed wheels adapted to directly engage the opposite faces of the record itself for rotating the record, control means responsive to the signal modulations for automatically rendering said feed wheels effective to rotate the record, means for applying the signal modulations to said control means, said control means including a delay device for causing the said feed wheels to continuously engage and rotate the record during brief intervals between successive portions of the signal and means for energizing the signal recording means with the signal modulations.

4. The combination as set forth in claim 3 in which the delay device is adapted to render the said feed wheels ineffective to rotate the record a short time after the termination of the application of the signal modulations to the control means.

5. A device for recording a signal having tone modulations on a record comprising, in combination, recording means adapted to record the signal on a record, rotatable means adapted to rotate the record, an electron discharge tube amplifier device having input and output circuits, means for applying the signal modulations to the amplifier input circuit, means for energizing the recording means with the amplified signal modulations appearing in the output circuit of the amplifier, a relay device coupled to the output circuit of the amplifier, and control means comprising a rotatable step-by-step device actuated by said relay device for causing the rotation of the record under the action of

said rotatable means in response to the amplified signal modulations.

6. A combination as set forth in claim 5 in which the control means comprises a delay relay arranged to cause the continuous rotation of the record during brief intervals between successive portions of the signal, a circuit including a switch for energizing said delay relay and means energized by the amplified signal modulations for closing said switch.

7. A device for recording dictation on a thin disc record of small mass and inertia comprising, in combination, stationary means for supporting the record, means for rotating the record including a friction roller mounted for movement towards and away from the record, means for maintaining the friction roller normally out of engagement with the surface of the record and means responsive to the operator's voice arranged to automatically move the friction roller into direct frictional engagement with the surface of the record to rotate it.

8. A device for recording dictation on a record comprising, in combination, a feed wheel for frictionally driving the record, control means operable step by step to engage the feed wheel with the record and to disengage the feed wheel from the record at alternate steps, and means controlled by the operator's voice for actuating the control means step by step.

9. A device for recording a signal having tone modulations on a record comprising, in combination, recording means adapted to record the signal on the record, rotatable means adapted to rotate the record, an electron discharge tube amplifier device having input and output circuits, means including a microphone for applying the signal modulations to the amplifier input circuit, means for energizing the recording means with the amplified signal modulations appearing in the output circuit of the amplifier and control means including a sound pressure relay for causing the rotation of the record under the action of said rotatable means.

10. A combination as set forth in claim 9 in which the control means includes a delay relay connected to the sound pressure relay and in which the sound pressure relay is disposed adjacent to the microphone.

11. A device for recording as a continuous signal on a thin disc record of small mass and inertia a series of signals previously recorded discontinuously on a second record, the device comprising, in combination, recording means adapted to record the signal on the thin disc record, means for rotating the first record with reference to the recording means, a stationary member engaging the lower face of the thin disc record for supporting it, means for continuously advancing the second record, means for energizing the signal recording means in accordance with the signals recorded on the second record and means responsive successively to each of the recorded signals on the second record to automatically render the record advancing means effective to alternately rotate and stop the thin disc record.

12. A device for recording as a continuous signal on a thin disc record of small mass and inertia a series of recorded discontinuous signals, the device comprising, in combination, recording means adapted to record the signal on the record, means for rotating the record with reference to the recording means, a stationary member engaging the lower face of the record

for supporting it, means for energizing the signal recording means in accordance with the recorded signals and means responsive successively to each of the recorded signals for automatically rendering the record rotating means effective to alternately rotate and stop the record.

13. The device as set forth in claim 12 in which the recorded signals comprise a plurality of sound tracks formed on separate thin flexible records.

14. A device for recording signal modulations transmitted by radio frequency carrier currents on a record, the device comprising, in combination, recording means adapted to record the signal modulations on the record, means adapted to advance the record with reference to the recording means, means responsive to the carrier currents for automatically rendering the record advancing means effective to advance the record and means for energizing the signal recording means in accordance with the signal modulations.

15. A combination as set forth in claim 14 in which the means responsive to the carrier currents includes means for automatically rendering the record advancing means ineffective to advance the record upon the disappearance of the carrier waves.

16. A device for recording signal modulations transmitted by radio frequency carrier currents on a record, the device comprising, in combination, recording means adapted to record the signal modulations on the record, means adapted to advance the record along the path of the recording means, a radio receiver having input and output circuits, means connecting said recording means to the receiver output circuit and control means whereby the tuning of the receiver input circuit to the carrier frequency automatically renders the record advancing means effective to advance the record.

17. A combination as set forth in claim 16 in which the radio receiver is of the superheterodyne type and comprises an intermediate frequency amplifier tube and in which the control means comprises a relay connected to the plate circuit of the amplifier tube.

18. A device for recording signal modulations transmitted by radio frequency carrier currents on a disc record, the device comprising, in combination, a recording unit having a stylus adapted to engage the record and record the signal modulations thereon, means arranged to rotate the record under the stylus, means responsive to a received carrier current for automatically rendering the said record rotating means effective to rotate the record, means for amplifying the signal modulations and means for energizing said recording unit by the amplified signal modulations.

19. A device for recording the signal modulations of a carrier wave on a record comprising, in combination, means for advancing the record, a radio receiver tunable to the carrier wave and having an electron discharge tube amplifier, and an automatic volume control device arranged to regulate the potential of the grid of said discharge tube inversely in accordance with the strength of a received carrier wave, means energized by the amplified signal modulations for recording the signal modulations on the record and means responsive to the adjustment of the potential of the grid of said discharge tube by said automatic volume control device to a predetermined value for initiating

the advancement of the record by said record advancing means.

20. A device for recording dictation on a thin flexible record of small mass and inertia comprising, in combination, a stationary member arranged to engage the lower face of the record for supporting it, rotatable driving means comprising a friction roller for rotating the record,

control means operable step by step to engage the friction roller with a face of the record and to disengage the friction roller from said face at alternate steps, and means controlled by the operator's voice for actuating the said control means step by step.

FERDINAND C. W. THIEDE.
